D10-23. DR D 2,968 EX

Design For Clock Front

Nº 2968

PATENTED
MAR 31 1868

United States Patent Office.

ELIAS INGRAHAM, OF BRISTOL, CONNECTICUT.

Design No. 2,968, dated March 31, 1868.

DESIGN FOR A CLOCK-FRONT.

The Schedule referred to in these Letters Patent and making part of the same.

TO ALL WHOM IT MAY CONCERN:

Be it known that I, ELIAS INGRAHAM, of Bristol, county of Hartford, and State of Connecticut, have invented or produced a new and original Design for Clock-Front; and to enable others skilled in the art to make or produce the same therefrom, I will proceed to describe by referring to the photographic views, in which the same letters indicate like parts in each of the figures.

In the accompanying drawings or photograph views are shown a new and original design for a clock-front. *a* is a plain round-moulded sash. *c* is a plain recess-surface underneath said sash. *d* are plain-figured relief rosettes upon the outer sides of the recess-surface; the whole combined to produce a plain, rich design for a clock-front.

What I claim, therefore, and desire to secure by Letters Patent, is—

The design for a clock-front, as hereinbefore illustrated and described.

ELIAS INGRAHAM.
